GLOVE

Marinette Blanc, New York, N. Y., assignor to
 Picardy Mills, Inc., Brooklyn, N. Y., a corpora-
 tion of New York

Application February 20, 1941, Serial No. 379,788

10 Claims. (Cl. 2—162)

My invention relates to gloves and its novelty consists in the adaptation and combination of parts as will be more fully hereinafter pointed out.

There have been many women who wished to purchase long gloves for daily use which came well up on the arms but have felt that they could not afford them as they were not adapted to use with most of their costumes.

My invention overcomes this great objection to the daily use of the long glove and makes it practicable for the first time with any and all costumes by making the length adjustable in a practical and attractive manner.

Referring to the drawing—

Figure 1 is a top plan view of the front of my right hand glove in the full extended position;

Figure 2 is a top plan view of the front of my left hand glove with the glove in the shortened and Shirred position; and

Figure 3 is a longitudinal cross section on the line 3—3 of Figure 1.

In the drawing of my glove which is stitched together in the usual way at 4 is the hand portion of my glove and 5 and 5^a are the arm portions. On the underside of the arm portions 5 and 5^a designated as 6 and 6^a respectively are stitched at 7 pockets 8 and 8^a respectively forming decorative members 9 on the outer faces 5 and 5^a.

In the pocket 8 are mounted two draw strings 10 and 11 which are stitched at one end to the base of said pocket at 12 and pass out through an opening 13 in the arm portion 5 at their opposite ends and said strings 10 and 11 terminate in stitched coils 14 and 15 which serve as grips for pulling as well as decoratively. On the underside of 5^a is similarly stitched pocket 8^a and draw strings 10^a and 11^a are mounted therein and are stitched at one end to the base of said pocket at 12^a and pass through the opening 13^a at the opposite end and terminate in stitched coils 14^a and 15^a.

The operation of my glove is very simple and when it is desired to shorten the front section of my glove so that it will not go up onto the arm the draw strings 10 and 11 can be pulled by taking hold of the stitched coils 14 and 15 and pulling thereon which will pull the arm portion 5 of the glove from the base 12 so as to draw the upper arm portion 5 toward the hand portion 4 effecting a Shirring of the arm portion 5 as shown in Fig. 2 and substantially shortening the arm portion 5 by means of the Shirring 16 shown in Fig. 2.

The back section of 5 may be shortened and Shirred in a similar manner by pulling on draw strings 10^a and 11^a effecting the pull at 12^a and the draw strings 10^a and 11^a may be fastened together in the same manner as shown at 17 in Fig. 2 so that the glove will be secured in the shortened position and the decorative Shirring 16 maintained in position.

It will be noted that 19 is merely decorative stitching.

It will be apparent that this shortening may be done and then knots tied either before or after the gloves are put on by the wearer, but that in order to secure perfect uniformity and the best result in appearance both the front and the back sections 5 and 5^a should both be shortened in each glove.

Variations may be made in the structure as shown and described without departing from the spirit and intent of my invention.

It will be understood that my gloves may be made of leather, fabric, a combination of these two or of any other material adapted for making gloves and may be made in all colors available in such materials.

I claim:

1. In an arm length glove, longitudinally adjustable means carried by said arm portion for shortening the arm portion of said glove and fastening the same in said shortened position.

2. In a glove means for shortening the arm portion of said glove comprising a draw string pocketed in the back arm portion one end of which draw string is secured to the base of said pocket near the upper arm end and the other end of said draw string being free at the wrist portion of said glove.

3. In a glove means for shortening the arm portion of said glove comprising a pair of draw strings pocketed in both the back arm portion and the front arm portion, one end of both pairs of which draw strings are secured at the base of each of said pockets near the upper arm end and the other ends of said pairs of draw strings being free at the wrist portion of said glove.

4. In an arm length glove, longitudinally adjustable means carried by said arm portion for Shirring the arm portion of said glove and means for fastening the same in said Shirred position.

5. In a glove means for Shirring the arm portion of said glove comprising a pair of draw strings pocketed in the front arm portion, one end of which pair of draw strings are secured to the base of said pocket near the upper arm end

and the other pair of ends being free at the wrist portion of said glove.

6. In a glove means for shirring the arm portion of said glove comprising a draw string pocketed in the back arm portion one end of which draw string is secured to the base of said pocket near the upper arm end and the other end of said draw string being free at the wrist portion of said glove.

7. In a glove means for shirring the arm portion of said glove comprising a pair of draw strings pocketed in both the back arm portion and the front arm portion, one end of both pairs of which draw strings are secured at the base of each of said pockets near the upper arm end and the other ends of said pairs of draw strings being free at the wrist portion of said glove.

8. In a glove having an arm portion a pair of draw strings pocketed in the front arm portion and a second pair of draw strings pocketed in the back arm portion, one end of both of said pairs of draw strings being secured to the base of said pockets near the upper arm end and both of the

other pairs of ends being free at the wrist portion of said glove so that each of said pairs of draw string free ends may be fastened together.

9. In a glove having an arm portion a pair of draw strings pocketed in the front arm portion and a second pair of draw strings pocketed in the back arm portion, one end of both of said pairs of draw strings being secured to the base of said pockets near the upper arm end and both of the other pairs of ends being free at the wrist portion of said glove so that each of said pairs of draw string free ends may be drawn and fastened together to effect a shirring and shortening of the arm portion.

10. In a glove, a single adjustable means for shortening and shirring the arm portion of said glove and fastening the same in said shortened and shirred position comprising a draw string carried by the arm portion one end of which draw string is secured to the upper arm end of the glove and the other end of said draw string being free at the wrist portion of said glove.

MARINETTE BLANC.
